(57) **CLAIM**

I claim the ornamental design for the breast prosthesis, as shown and described.

DESCRIPTION

FIG. 1 is a front elevation of a breast prosthesis showing my new design;

FIG. 2 is a left side elevation thereof;

FIG. 3 is a rear elevation thereof;

FIG. 4 is a right side elevation thereof;

FIG. 5 is a top plan view thereof;

FIG. 6 is a bottom plan view thereof;

FIG. 7 is a front elevation of the design shown in FIGS. 1 through 6 showing snap type fastener attachments in broken lines which form no part of the claimed design;

FIG. 8 is a left side elevation thereof;

FIG. 9 is a rear elevation thereof;

FIG. 10 is a right side elevation thereof;

FIG. 11 is a top plan view thereof;

FIG. 12 is a bottom plan view thereof;

FIG. 13 is a front elevation of the design shown in FIGS. 1 through 6 showing hook and loop type fastener attachment in broken lines which form no part of the claimed design;

FIG. 14 is a left side elevation thereof;

FIG. 15 is a rear elevation thereof;

FIG. 16 is a right side elevation thereof;

FIG. 17 is a top plan view thereof; and,

FIG. 18 is a bottom plan view thereof.

The breast prosthesis for the side opposite that shown in the figure drawings is a mirror image thereof.
